US0D1077570S

(12) **United States Design Patent** (10) Patent No.: **US D1,077,570 S**
(45) Date of Patent: ** Jun. 3, 2025

(54) **BLENDER**

(71) Applicant: **NUC ELECTRONICS CO., LTD.**,
Daegu (KR)

(72) Inventor: **Jong Boo Kim**, Daegu (KR)

(**) Term: **15 Years**

(21) Appl. No.: **35/521,664**

(22) Filed: **Jul. 6, 2023**

(80) **Hague Agreement Data**

Int. Filing Date: **Jul. 6, 2023**

Int. Reg. No.: **DM/232684**

Int. Reg. Date: **Jul. 6, 2023**

Int. Reg. Pub. Date: **Jul. 12, 2024**

(30) **Foreign Application Priority Data**

Jan. 9, 2023 (KR) 30-2023-0000997
